ROWLAND T. WALES, OF NEW ROCHELLE, NEW YORK, ASSIGNOR OF ONE-HALF TO
ARTHUR C. FRASER, OF NEW YORK, N. Y.

WIRE CLAMP FOR CONCRETE FORMS.

Application filed May 12, 1923. Serial No. 638,535.

This invention relates to wire ties for holding together the opposite sides of concrete forms against internal pressure of the concrete before the latter solidifies. Such ties are sometimes made of rods held near their ends by clamps, but as difficulty is encountered in either pulling such rods out of the green concrete or cutting off their protruding ends, the better practice is to use tie wires. Such wires have been either stretched singly across the mold space, or in most cases a doubled tie wire has been used, and the common practice has been to tighten it by inserting a cross-bar between the wires at the middle and by turning it to twist them after the manner of a tourniquet. For both single and doubled wires also screw tightening means have been proposed, but heretofore none of these have been sufficiently effective to secure wide adoption. The present invention aims to provide an improved construction whereby the tightening is accomplished by means wholly outside of the mold space, and which enables a single wire to be used.

The tie comprises any suitable anchor bearing against one side of the form to which the wire on that side is fastened, and an anchor on the other side of the form (which may or may not be like the first anchor), and tightening means in relation with the latter anchor, by which the wire may first be tightened and then attached to such anchor. When the wire has thus been securely anchored on both sides of the form, the tightening means may be disconnected and removed.

The invention in its preferred form is shown in the accompanying drawings, wherein,—

Figure 1 is a horizontal section showing a fragment of a concreting form with the wire tie in place;

Fig. 2 is a horizontal section of a somewhat different construction of mold with the wire tie in place;

Fig. 3 is a front elevation of part of the mold shown in Fig. 2;

Fig. 4 is a perspective view showing the preferred form of anchor;

Fig. 5 is a fragmentary vertical section of a mold such as that shown in Fig. 1, illustrating the operation of applying the tie by means of the wire tightener. The tightener is shown partly broken away in mid-section;

Figs. 6 and 7 show the tightener on a larger scale, Fig. 6 being a plan looking downward in the position shown in full lines in Fig. 5, certain of the parts being in longitudinal mid-section. Fig. 7 is an elevation viewed from the left in Fig. 6;

Fig. 8 is a detail viewed from the right in Fig. 6.

Fig. 9 shows a part of the tightener.

Referring first to Figs. 1, 2 and 3, A and A' are the opposite forms constituting the mold for a concrete wall, the space B between these being the mold space to be filled with concrete. Such forms are commonly made with mold boards or panels C C which usually extend horizontally and are held by upright framing or studs D D of wood or metal. In Fig. 1 the studs D D are arranged in pairs. In Fig. 2 the upright studs D D are more widely spaced, and outside of them are horizontal stretches of strips E E to form a bearing for the tie plates or anchors. With either construction of form a spacing stick F is introduced at intervals to hold the opposite form plates C C apart, these sticks being taken out as the concrete is filled into the mold. These sticks are preferably placed adjacent to the wire ties G G which hold the opposite form walls together and resist the outward or bursting strain of the concrete.

In either construction the wire clamp construction is the same except for the arrangement of the anchors.

J and K are anchors or tie plates to which the opposite ends of the tie wire G are fastened. The anchors J K may be duplicates of one another, as shown, or they may be of different construction. In the construction shown, which is illustrated in detail in Fig. 4, each anchor consists of a flat plate a adapted to lie and bear against the flat outer face of the form (either the outer faces of the studs D D in Fig. 1, or of the strips E E in Figs. 2 and 3), and has an opening b through which the wire passes; attached to the plate a is a suitable form of projection adapted for the attachment thereto of the end portion of the wire. In the preferred construction this attaching or cleat portion 95 of the anchor is constructed as a wall c projecting from the plate a at preferably right angles, and having a notch d for receiving and engaging the wire, and notches e and f for fastening the wire. The construction is 100 105 110

such that the anchor may conveniently and cheaply be made by cutting from rolled angle iron and punching the holes and notches. The plate *a* has preferably also a hole *g* near one end, through which a nail may be driven.

The tie wire *G* is connected or attached to each anchor in the manner shown, namely, by passing its end through the opening *b* and bending it down into the notch *d*, then bending it to one side and carrying it into the notch *c*, thence along the opposite side and into the notch *f*, so that the end portion of the wire is held by the portion *h* of the wall beyond this notch. The opening *b* and the notch *d* are both made by preference with tapered sides, so that the wire being first introduced through the larger portion is drawn between these tapered sides and thereby gripped.

One end of the wire tie is first fastened in any suitable way to any suitable kind of anchor or attaching means, to come against one side of the form, as shown at *J*, and the wire is then passed through the form, the anchor *K* shown in Fig. 4 being placed against the other side with the wire passing through its opening *b*, and the tightener, which will now be described, is brought into engagement with this anchor in order first to tighten the wire to the requisite tension, and then to bend the wire down into engagement with the notch *d*, so that the wire may be securely held until further fastened. For the anchor *J* it is desirable, for convenience, to use the same construction as shown in Fig. 4, but all essential requirements will be met by using any known or suitable type of anchor to which the wire may previously be attached, and which may be applied in the position of the anchor *J*.

The tightener, which is shown in working position in Fig. 5, and more in detail in Figs. 6 and 7, comprises a base or foot *L* for engaging the anchor *K*, a frame *M* projecting therefrom for supporting and receiving the reaction of a rotatable nut *P*, and a screw *Q* passing through and engaged by said nut, and having means for clamping the end portion of the wire. Preferably the screw *Q* is made tubular, and the clamping means consists of an enlargement or head *k* thereon into which engages a screw *l* having a crosshead *m* for turning it, so that it serves as a set-screw for clamping the wire which has been thrust into the hollow of the screw *Q*. The nut *P* is turned by an arm *p* having a crank handle *p'*. It is desirable to make this crank adjustable to varying lengths of throw, for which purpose the arm *p* is slidable in a clamping head *P'* formed on the nut, and is engaged and locked in any adjusted position by means of a set-screw *q*. The nut turns in a collar *R* which is a part of the frame *M*, and is formed preferably

integrally with the arms thereof, which are arranged somewhat as in the letter *A* and serve as struts to transmit the reactive stress to the base *L*. The base *L*, which is shown separately in Fig. 9, is shaped to fit over the outstanding flange *c* of the anchor *K*. Accordingly, it has a recess terminating at the sides in notches *r r* for receiving the ends of the projecting flange *c*, and for centering the base thereon. The base has a flat portion *s* which bears against the plate *a* of the anchor. The middle portion of this is displaced upwardly as an arch to afford ample room for the entrance of the wire, whatever may be its position in the opening *b*. This arched portion is lettered *t*. The base also has downwardly-extending bracket portions *u u* for giving it an extended bearing upon the outer face of the form. At its sides the base has a pivotal connection with the frame *M*, preferably formed by providing the base with cylindrical projections *v v* entering holes in eyes formed at the base ends of the two legs of the frame *M*; when these parts are applied, washers *W* are placed outside of them, and cotter pins *x* or other fastening means are used to hold the parts together. Thus, the frame *M* is pivoted so that it may swing around the axis of the journal projections *v v*, and hence may be swung from the position shown in full lines in Fig. 5, downward to that shown in dotted lines. For properly locating the frame *M* in its upper position by preventing its being carried too high, a stop or brace piece *M'* is provided, which is shown as riveted at its upper end to the frame *M* adjacent the collar *R*, and having a brace *m'* near its lower end which is riveted to one of the legs of the frame near its pivotal eye.

In operation, after the wire has been put through the form, the anchor plate *K* has its opening *b* threaded over the wire, and the plate is placed against the outer face of the form and then preferably fastened temporarily by driving a nail into the hole *g*. The tightener is then applied by placing its base *L* over the projecting flange *c* of the anchor, while introducing the end of the wire through the flaring hole in the head *k*, and up through the hollow of the screw *Q*. Previously the screw *Q* was advanced sufficiently toward the base *L* to give the requisite range of tightening movement. When the tightener has thus been brought into position, the screw *l* is tightened to cause its end to clamp the wire firmly. Thereupon the operator turns the nut *P* by means of the crank *p, p'*, and thereby propels the screw *Q* outwardly. The screw is prevented from turning in any suitable manner, the simplest way being by utilizing the projecting screw *l* as a means to this end by confining it between two members of the frame *M*, so that when the rotat-

tion has turned it into contact with either member it cannot turn farther, and the screw then remains non-rotative. The outward movement of the screw Q thus acts to stretch the wire until the desired tension is attained. Then the operator bears down on the tightener, forcibly bending it down to the position shown in dotted lines in Fig. 5. The result of this is to bend the tie wire G into the notch *d* and force it down between the approaching walls of this notch until it is caught and bitten thereby. The same movement draws it down into the narrower portion of the notch or opening *b*, so that the wire is given a biting engagement in two places, and at the same time by being forcibly bent downward under tension is given a set, so that it cannot spring back. If necessary, this biting effect may be increased by striking a blow with a hammer against the wire below the flange *c*, which forces it deeper into the notch *d*. The operator may then release the screw *l* so as to free the wire and disconnect the tightener and remove it. To make the fastening of the end portion of the wire more complete and secure, the operator then, by means of a hammer or otherwise, turns the wire sidewise and bends it up through the notch *e*, then bends it horizontally across the top of the flange *c*, and forces it into the notch *f* and beneath the projection *h*, all as shown in dotted lines in Fig. 4. The wire end is thus so securely attached that it cannot escape from its biting engagement with the notches *b* *d*.

The operation thus described is very quickly performed and results in the effective tightening of the wire to any desired tension, and its secure anchorage, so that the concrete mold or form cannot open up under the internal or expanding pressure of the wet concrete. When the concrete has set or solidified, and the form (or its lower portion) is to be released, it is only necessary to either unbend the wire or cut it, the latter being the usual course. Then by removing the nail driven at *g* and straightening the cut end of the wire, the anchor or cleat *K* may be removed and preserved for repeated future use. If the anchor *J* is of the same construction, this operation may be performed alike on both sides of the form. When the form is sufficiently removed to give access to the face of the concrete wall, the projecting wires may be cut at the surface or twisted off beneath the surface and the opening pointed over; or if it is preferred not to leave the wire ties in the wall, these may be pulled out therefrom while the concrete is still green.

For pulling the tie wires from the wall the same tightening instrument is useful. For this purpose the projecting end of the wire is straightened sufficiently to enable it to be introduced within or through the hollow of

the screw *Q*, whereupon the wire is clamped therein by the set-screw *l*, and by rotating the nut *P* a powerful pull is generated, so that the wire may be pulled free from the green concrete and thereafter easily withdrawn from the wall. This operation is best performed before stripping the mold. It is desirable to broaden the base *L* by using with it one of the anchors *K*. For use as such wire puller the tightener may well be applied upside down as compared with Fig. 5, because it is not required to swing downwardly, and its brace *M* then serves to prevent its dropping below a horizontal position.

In the description of the operation above given, it is understood that the anchor *K* is applied horizontally against upright studs, as shown in Figs. 1 and 5; if the construction of concreting form shown in Figs. 2 and 3 is used, where the anchor is arranged vertically, so as to bear upon two closely adjoining strips *E*, *E*, the operation is modified only to the extent that the tightener is swung horizontally to the left (or right) instead of downwardly, in order to draw the wire into the converging notches.

The anchors and tightener provided by the present invention are applicable to practically every known construction of concreting forms or molds. The two simple constructions of wooden forms shown in Figs. 1, 2 and 3 are the ones most commonly used. The invention is, however, equally applicable to sectional metallic forms.

All prior constructions of wire ties for concreting forms have required the use of a tightening screw or other tightening means for each wire tie; the present invention has the important economic advantage of dispensing with all tightening means except temporarily during the time when the tightening is being performed. Thus, on an erecting contract requiring, for example, 10,000 wire ties, the former constructions would have required an equal number of tightening screws or equivalent tightening devices, while the present invention requires only one tightening device, or one to each workman who is to do the tightening of the ties, so that in the given example from one to perhaps ten tighteners only would be needed, as against 10,000. The improved anchors herein described are extremely cheap and afford absolute assurance of a non-yielding grip upon the wire which cannot give way during the concreting performance.

While the preferred embodiment of the invention has been described in detail, it is to be understood that the invention is not confined to this precise construction, but may be greatly modified or varied within the scope of the appended claims.

The anchors *J* or *K* are useful in some situations without cooperation with the

tightener, and for this reason the anchor is separately claimed in a divisional application filed May 22, 1926, Serial No. 110,902. For the purposes of the present invention, which includes the anchor and tightener in their cooperative relation, it is essential that the anchor be adapted to make a suitable engagement with the tautened wire so as to securely hold it while the tightener is being detached and removed, after which the wire may be more permanently attached to the anchor if necessary. For the purpose of such engagement the tapered opening or openings *b d* (or equivalent means) are formed on a fixed or integral part of the anchor, as distinguished from using a separate movable fastening means such as a set screw.

I claim as my invention:—

1. A wire clamp for concrete forms comprising anchors on opposite sides of the form, a wire attached to one anchor, and a tightener engaging the wire and the other anchor for tautening the wire, the latter anchor having an integral fixed portion adapted to grip the taut wire while held by said tightener.

2. A wire clamp for concrete forms comprising anchors on opposite sides of the form, a wire attached to one anchor, and a tightener engaging the wire and the other anchor for tautening the wire, the latter anchor being integral and having rigid means for gripping the taut wire, and the tightener movable to carry the wire into gripping engagement by said means.

3. A wire clamp for concrete forms comprising anchors on opposite sides of the form, the wire attached to one anchor, and a tightener engaging the wire and the other anchor for tautening the wire, the latter anchor having an opening for receiving the wire, such opening having converging sides adapted to grip the wire as the latter is drawn into its narrower portion, and the tightener movable to carry the taut wire into such narrower portion.

4. A wire clamp for concrete forms, comprising anchors on opposite sides of the form, the wire attached to one anchor, and a tightener engaging the wire and the other anchor for tautening the wire, the latter anchor having an opening for receiving the wire, such opening having converging sides adapted to grip the wire as the latter is drawn into its narrower portion, and having a projecting part with a second opening with converging sides, and the tightener movable to carry the taut wire into the narrower portion of said first-named opening and to subsequently carry the wire into the narrower portion of said last-named opening, whereby the wire is doubly gripped by the anchor.

5. A wire clamp according to claim 2, the

tightener adapted to disengage the wire after the latter has been gripped by the anchor.

6. A wire clamp according to claim 4, the tightener adapted to disengage the wire after the latter has been gripped by the anchor. 70

7. In a wire clamp for concrete forms, a tightener comprising a frame for reacting against the form, and tightening means movable relatively to the frame and perpendicularly to the form for tautening the wire, 75 the frame movable to bend the wire after tautening.

8. A wire clamp for concrete forms, a tightener comprising a frame for reacting against the form, and tightening means comprising a hollow screw entered by the wire, with means for gripping the wire thereto, and a rotary part engaging the screw for tautening the wire, the frame movable to bend the wire while taut. 85

9. In a wire clamp, a tightener comprising a frame adapted to seat against a wire anchor, and tightening means movable in said frame to tauten the wire, and the frame rotatable around its engagement with the anchor to bend the taut wire. 90

10. In a wire clamp, a tightener comprising a base, a frame pivoted thereto, and tightening means movable in said frame, the base adapted to engage an anchor, and the frame movable on its pivotal engagement to bend the taut wire. 95

11. In a wire clamp, the combination with an angle plate anchor of a tightener comprising a base adapted to fit against such anchor and engage its projecting portion, a frame pivoted to said base, and tightening means movable in said frame to tauten the wire, the frame adapted to turn on said pivotal engagement to bend the taut wire. 100

12. In a wire clamp, a tightener comprising a frame, a hollow screw, a rotatable nut engaging said screw and mounted to turn on said frame, and a set screw carried by said screw for gripping the wire and projecting into engagement with the frame to limit the rotation of the screw. 110

13. A tightener according to claim 7, having a stop to engage the form when in the wire-tightening position. 115

14. A tightener according to claim 7, having a brace on one side reacting against the form when in the wire-tightening position.

15. In a wire clamp, the combination with an anchor of a tightener adapted to fit against the anchor, having means for tautening the wire, and movable relatively to the anchor to bend the taut wire, and the anchor having fixed integral means for gripping the wire as the latter is bent into engagement therewith. 120

16. A wire clamp for concrete forms comprising anchors on opposite sides of the form, a wire attached to one anchor, and a tightener engaging the wire and the other 125

anchor for tautening the wire, the latter anchor having rigidly fixed means for engaging the taut wire, and the tightener adapted to disengage the wire and be detached after the anchors are united by the taut wire.

17. In a wire clamp tightener comprising a frame, a hollow screw, a rotatable nut

engaging the threads of the screw and having a swivel attachment to the frame, means for attaching the wire to the screw, and means for limiting rotation of the screw as the nut is turned. 10

In witness whereof, I have hereunto signed my name.

ROWLAND T. WALES.
